ATTORNEYS.

UNITED STATES PATENT OFFICE.

FRANKLIN TOMPKINS, OF NEW DORP, NEW YORK.

ROTARY ENGINE.

No. 913,927.

Specification of Letters Patent.

Patented March 2, 1909.

Application filed January 2, 1909. Serial No. 470,385.

To all whom it may concern:

Be it known that I, FRANKLIN TOMPKINS, a citizen of the United States, and residing at New Dorp, Staten Island, in the county of 5 Richmond and State of New York, have invented certain new and useful Improvements in Rotary Engines, of which the following is a specification, such as will enable those skilled in the art to which it appertains to 10 make and use the same.

This invention relates to rotary engines, pumps and other apparatus of this class, and particularly to apparatus of this class that employs a cylindrical casing in which is eccentrically mounted a rotatable piston member provided with radially movable piston blades; and the object of the invention is to 15 provide an apparatus of the class specified in which the rotatable member and radially 20 movable blades are so formed as to prevent the cramping, twisting or locking of the said blades when in their outermost position or at the limit of their outer movement; and with this and other objects in view the invention 25 consists in an apparatus of the class specified, constructed as hereinafter described and claimed.

The invention is fully disclosed in the following specification, of which the accompanying 30 drawing forms a part, in which the separate parts of my improvement are designated by suitable reference characters in each of the views, and in which:

Figure 1 is a sectional side elevation of a 35 rotary pump casing and inclosed parts made according to my invention; Fig. 2 a section on the line 2—2 of Fig. 1; and, Fig. 3 a view similar to Fig. 1 but showing a modified arrangement of the rotary member and piston 40 blades.

In the practice of my invention, as shown in Figs. 1 and 2, I provide a cylindrical casing *a*, one side *a*² of which is detachable and in which is eccentrically mounted the rotary 45 member *b*. The rotary member *b*, in the form of construction shown, is cross-shaped in form or provided with radial arms *b*², four of which are shown, and said rotatable member is provided with trunnions *b*³ one of 50 which has a bearing *b*⁴ in the detachable side *a*² of the casing *a*, and the other of which passes through the opposite side of said casing and through a stuffing box device *a*³ connected therewith and forms a power shaft *b*⁵ with 55 which may be connected a belt or other power transmitting device of any kind or

class. The radial arm members *b*² of the rotatable part *b* are slotted longitudinally as shown at *b*⁶, and these slots extend through the central portion of the rotary member as 60 clearly shown in Fig. 1, the slots in the opposite arms *b*² being in communication through the center of said rotary member.

Mounted in the slots *b*⁶ in the radial arm members *b*² are radially movable blades *c*, and these blades are provided at their opposite side edges and adjacent to their inner faces with side trunnions *c*² movable in concentric grooves *c*³ formed in the ends or opposite side portions of the casing *a*, said grooves 70 being formed around the central axis of said chamber and concentric therewith, while the trunnions of the rotary member *b* are eccentric to said axis. With this construction, it will be seen, that as the member *b* rotates the 75 blades *c* are given a radial movement and in one position of the rotary member *b*, or at one point of its rotation, the blades *c* are almost entirely projected from the radial arms or arm members *b*² of said rotary member as 80 clearly shown at the bottom of Figs. 1, and 2, and in order to prevent the blades *c* in this position from cramping, twisting or locking by reason of their contact with the inner walls of the cylindrical casing, I provide the 85 inner edges or faces of said blades with parallel projecting members or fingers *c*⁴ which pass through the central portion of the rotary member *b* in the radial movement of said blades, and these projecting members or fingers *c*⁴ on the blades *c* are so arranged that the said members or fingers on two opposite blades *c* interlock when said blades are in their innermost position, while the projecting fingers or members *c*⁴ on the other two blades 95 *c* also interlock when said blades are in their innermost position, and the fingers or members *c*⁴ of one pair of blades cross the fingers or members *c*⁴ of the other pair of blades as clearly indicated in Figs. 1 and 2.

It will be understood, of course, that the fingers or members *c*⁴ of the blades *c* strengthen and brace said blades when in their outermost position and prevent the same from cramping, locking or twisting because of the pressure of the outer faces thereof on the inner wall of the casing *a*.

Independent of the rotary member *b* and the radially movable blades *c*, the entire apparatus is similar in construction and operation to other apparatus of this class and especially similar to the construction described

and claimed in an application for Letters Patent of the United States filed by me Feb. 18, 1908, Serial No. 416,512 which application was allowed Dec. 8, 1908, and the casing 5 *a* is provided at its opposite sides with inlet and outlet ports or passages *d* and *d*² through which steam is admitted to and escapes from the said casing.

My invention is not limited to the exact 10 form of the rotary member *b* herein shown and described, and this rotary member may be formed in the same manner as in the application above referred to, or as sometimes formed in other apparatus of this class, and 15 it is immaterial whether the rotary member be mounted on, or forms a part of a shaft, all that is necessary in any construction of this kind being that the radially movable blades *c* be mounted in radial recesses which extend 20 through the center of the rotary member in order that the fingers or members *c*⁴ on the blades *c* may have sufficient play in said rotary member to accommodate the operation of said blades.

25 In Fig. 3 I have shown a modification in which a casing *e* is employed, said casing consisting of two cylindrical parts *e*² which are in communication at *e*³ and in each of which is mounted a rotary member *f* having radial 30 projections *f*² which interlock as shown at *f*³ in the operation of the apparatus. The general form of this apparatus is one which is old and well known, but with my improvement the radially projecting parts *f*² of the 35 rotary member *f* are provided, as shown in Figs. 1 and 2, with the radially movable blades *c* having the trunnions *c*² movable in the concentric grooves *c*³, and said blades are provided as shown in Figs. 1 and 2 with 40 parallel projecting members or fingers *c*⁴ at their inner edges or faces which pass through the central portions of said radial members in the operation of the apparatus and as will be readily understood from the description 45 of the construction shown in Figs. 1 and 2, and with this or these exceptions the apparatus shown in Fig. 3 will be constructed in a manner similar to others of its class.

In practice, I also provide the trunnions *c*² 50 of the blades *c* with anti-friction bearings *g* which are free to turn on said trunnions within the grooves *c*³, and these bearings are shown in section in Fig. 2 and indicated in dotted lines in Fig. 1.

55 My invention is not limited to the exact details of the construction of the rotary member and the radially movable blades mounted therein as herein shown and described, and various changes in and modifications of this 60 construction may be made, in view of the appended claims, without departing from the

spirit of my invention or sacrificing its advantages.

Having fully described my invention, what I claim as new and desire to secure by Let- 65 ters Patent, is;—

1. In an apparatus of the class described, a cylindrical casing, a rotary member mounted eccentrically therein and provided with radially movable blades, said radially movable 70 blades being mounted in recesses which extend through the center of the rotary member, and said blades being provided at their inner edges with projecting fingers or members which move radially through the central portion of the rotary member in the operation of the apparatus, the fingers or members of opposite blades inter-locking, and the fingers or members of blades arranged at an angle to each other crossing 75 each other during said operation.

2. In an apparatus of the class described, a cylindrical casing the opposite sides or ends of which are provided with concentric grooves, a rotary member eccentrically 80 mounted in said casing and provided with radially movable blades having trunnions movable in said grooves, said blades being mounted in radial recesses formed in the rotary member and passing through the center 85 thereof, and the inner edges of said blades being provided with projecting portions which move through the central portion of the rotary member in the operation of said apparatus.

95 3. In an apparatus of the class described, a cylindrical casing the opposite sides or ends of which are provided with concentric grooves, a rotary member eccentrically mounted in said casing and provided with 100 radially movable blades having trunnions movable in said grooves, said blades being mounted in radial recesses formed in the rotary member and passing through the center thereof, and the inner edges of said blades 105 being provided with projecting portions which move through the central portion of the rotary member in the operation of said apparatus in such manner that the projecting portions of opposite blades interlock, and the projecting portions or blades arranged at 110 an angle to each other cross each other in said operation.

In testimony that I claim the foregoing as my invention I have signed my name in 115 presence of the subscribing witnesses this 31st day of December 1908.

FRANKLIN TOMPKINS.
